FIG. 13

UNITED STATES PATENT OFFICE.

HERBERT E. WHITE AND HENRY F. PHILIBIN, OF YOUNGSTOWN, OHIO, ASSIGNORS
TO THE GENERAL FIREPROOFING COMPANY, A CORPORATION OF OHIO.

METAL FURNITURE CONSTRUCTION.

1,374,868.

Specification of Letters Patent. Patented Apr. 12, 1921.

Application filed July 29, 1919. Serial No. 314,003.

To all whom it may concern:

Be it known that we, HERBERT E. WHITE and HENRY F. PHILIBIN, citizens of the United States, residing at Youngstown, in the county of Mahoning and State of Ohio, have invented certain new and useful Improvements in Metal Furniture Construction, of which the following is a specification.

10 This invention relates to metal furniture construction particularly of the character adapted for making metal filing cabinets and like devices.

15 A primary object of the invention is to provide a metal filing cabinet or like device comprising a plurality of unit parts designed with special reference to being placed in knocked-down condition for shipment in compact form, while at the same time capable of being readily set-up or assembled for use.

20 Another distinctive object of the invention is to provide a metal furniture construction of a simple character and economical to manufacture, and which, when set up for use, will equal the appearance of a solid cabinet, having all of the desirable qualities and characteristics thereof as to stability and rigidity.

25 30 With the above and other objects which will more readily appear as the nature of the invention is better understood, the same consists in the novel construction, combination and arrangement of parts hereinafter more fully described, illustrated and claimed.

35 The various details of the structure are necessarily susceptible of modification without departing from the scope of the invention, but a preferred and practical embodiment of the invention is shown in the accompanying drawings, in which:—

40 Figure 1 is a perspective view of the present improved cabinet with portions broken away to show the construction more clearly.

Fig. 2 is a front elevation of the cabinet.

Fig. 3 is a top plan view of the cabinet, with parts broken away.

45 Fig. 4 is a detail sectional view taken on the line 4—4 of Fig. 1.

50 Fig. 5 is a detail sectional view taken on the line 5—5 of Fig. 1, and showing a solid side panel substituted for skeleton construction.

55 Fig. 6 is a perspective view of an upper

front corner of the cabinet with portions thereof broken away to show the connection between the top, front and side sections of the cabinet.

Fig. 7 is a detail perspective view, partly 60 in section, to show how the front corner of the top plate is notched to clear the vertical members of the front section.

Fig. 8 is a detail perspective view partly 65 in section, showing one of the upper rear corners of the cabinet.

Fig. 9 is a detail perspective view of one of the rear upper corners of the cabinet, illustrating a modification of the invention.

Fig. 10 is a perspective view of a lower 70 rear corner of the cabinet when constructed in accordance with the plan shown in Fig. 9.

Fig. 11 is a detail perspective view of one 75 end of the spacer rods utilized for separating and holding the side ladder sections in spaced relation.

Fig. 12 is a diagram of the cabinet, showing the manner of assembling the side sections with reference to the back section.

Fig. 13 is a view similar to Fig. 1 showing 80 the front section fitted into the seat formed at the front edges of the opposite side sections, and the locking panels in position to hold the front and side sections locked together.

85 Similar reference characters, designate corresponding parts throughout the several figures of the drawings.

In carrying the present invention into effect it is proposed to provide a plurality 90 of sections or units, each of which may consist of more than one part and be completely assembled at the factory by welding, riveting, or otherwise, as may be found most convenient, but of such a form in each instance as to pack relatively flat for shipment. To that end the invention fundamentally and essentially comprises several interfitting and interlocking units which, though capable of being knocked-down for 95 shipment in compact relation, may also be easily and quickly set up to form a rigid cabinet structure complete in itself as a part in a series or stack of cabinets of like construction.

100 By reference to Figs. 3 and 12 of the drawings it may be observed that the present cabinet construction primarily includes the back sections A, the opposite side sections B—B, the bottom unit C, the top unit 110

or cap D and the front unit or ladder E. These units are adapted to be assembled in substantially the order named, as will appear after the structural features and characteristics of the several units have been elucidated.

Referring first to the back section, or key unit A, it will be observed that the same comprises a wall plate 1 having the opposite 10 holding flanges 2 formed at each edge thereof, said flanges being bent in such a manner as to provide inwardly facing grooves or channels for receiving parts of the side sections B as will presently appear. The 15 upper edge portion of the wall 1 of the back section A is formed with an inwardly disposed flange portion 3 bent up at 4 (Fig. 8) to provide an angle flange disposed at the same side of the wall 1 as the flanges 2—2. The vertical member 4 of the said angle flange has secured thereto in any suitable manner, angle plates 5, the leaf portions 6 of which are adapted to be disposed parallel to the flange 3, and spaced therefrom, to 20 provide a holding slot 7 for the rear edge of the cap section D, as hereinafter pointed out. The lower edge of the wall 1 of the back section is provided with a stiffening flange 1^a (see Fig. 1) and slightly above the 25 edge is fitted with a suitable angle member 8 for receiving the downturned flange or skirt portion of the bottom section C, as will also hereinafter more fully appear.

The side sections B—B are of skeleton 30 construction, and in their assembled form are of ladder-like formation, since the opposite vertical members thereof are joined by transverse members as shown for instance in Fig. 1 of the drawings. That is 35 to say, each side section B essentially consists of the front and rear inside upright members 9 and 10 respectively, which are connected by the horizontal drawer supporting members 11, to thus provide a rigid 40 structure. The uprights 9 are preferably of relatively wide channel formation (see Figs. 12 and 13) with the out-turned flange portions 9^a and 9^b, while the rear vertical 45 upright members 10 are also of relatively 50 wide channel formation and provided with the front abutment flange 12 and the rear substantially hollow keeper flange 13 which is adapted to fit into the inwardly facing channel or keeper groove of the flanges 2 of 55 the back section A. (See Figs. 8 and 12.) Accordingly, it will be apparent that the side sections B consisting of the front and rear upright members 9 and 10 and the transverse drawer supporting members 11 60 may be assembled at the factory in the form of a ladder as shown, so that they may be readily and quickly assembled with reference to the back section A.

For the purpose of facilitating the assembling of the side sections B with reference

to the back section A, it may be observed that after the keeper flanges 13 of the rear vertical uprights 10 have been fitted into the vertical channels or keeper grooves of the flanges 2, a stiffening angle iron 14 may 70 be placed in the angle formed at the inner meeting edges of the rear vertical uprights in the back section as shown in Figs. 1 and 12, wherein suitable perforations in the angle plate 14 will register with similar perforations in the uprights 10 to receive the reduced end portions 15 of the spacing rods 16 which not only serve as braces or stays for stiffening the rear structure of the cabinet, but also lock the side sections B to the 75 back section in a thoroughly practical and efficient manner.

The bottom plate C of the cabinet preferably consists of the body portion 17 having the down-turned side and rear flange 85 portions 18, the latter fitting into the channel formed by the keeper member 8 carried at the lower rear edge of the back section A, and the down-turned side flanges engaging with the holding clips 8^a carried 90 by the rear vertical members of the side sections B—B. (See Fig. 1.) Thus the bottom plate 17 securely holds the back and side sections together and generally stabilizes the lower end of the cabinet structure 95 by reason of the construction pointed out. The front edge of this bottom unit or plate is formed with an up-turned flange 19, and this flange cooperates with a front bottom panel member 20 shown in Fig. 1 of the 100 drawings to provide a finished appearance for the lower edge of the front of the cabinet.

The top section or cap D (see Fig. 8) is provided at all of its edges with down-turned flange portions for telescopically fitting over the side sections B—B and front and rear sections E and A, and for the purpose of providing a thoroughly effective lock joint between the cap, and the several sections on which it is surmounted, the rear downwardly turned flange 21, thereof, is provided with an inturned locking foot flange 22 which is adapted to slidably engage the top flange 3 of the back 1 and ride 115 into the slot 7 formed between the leaf 6 of the angle plate 5 and the said flange 3. The opposite side flanges 23 of the cap, as well as the front flange 24 thereof may be provided with the inwardly extending flange 110 elements 25 which have the down-turned lip portions 26 for providing a snug and dust-proof joint between the front and side edges of the cap and the corresponding parts of the vertical front and side sections. As 120 shown in Figs. 6 and 8 the inturned flange portions 25 are cut away at the corners to clear the upright members.

The front section E is also a complete unit in itself, and like the sections B—B is of 125 130

ladder formation, essentially comprising the opposite vertical side members 27, which are preferably of channel formation, and the transversely disposed drawer dividers 28. 5 Owing to the novel formation of the front uprights of the side ladders, the angularly formed flanges 9^b of the opposite ladders provide a seat for receiving the channeled upright members 27 of the front section, 10 and for the purpose of locking the entire front section E in position with reference to the side sections, suitable panel strips 29 are provided. These panel strips constitute one of the novel and distinctive features of the 15 present invention and are of substantially U-shaped formation, as may be observed from Figs. 1, 4, 12 and 13 of the drawings. The web portion 30 is exposed to view and constitutes a finished front side edge of the 20 cabinet, while the inner leaf member 31 thereof is notched as at 32 to clear the drawer dividers 28, and the outer leaf member 33 is provided with a locking hole 34 for registering with a similar locking hole 25 in the vertical upright members 9 of the side sections B—B to receive a fastening for connecting two adjacent cabinets together, and also for holding the panel members securely 30 in position to thereby fasten the front section E in place with reference to the side sections B—B.

When it is desired to set the cabinet up as a complete unit by itself, and have the sides thereof closed or protected, it is proposed to 35 provide a side wall S as suggested in Fig. 5 of the drawings, and this side wall S has its front edge formed in the same manner as the panel members 29. That is, it is provided with an inturned leaf portion having 40 notches for clearing the drawer dividers 28 and when used as shown in Fig. 1, for instance, the same may be secured to the channels 27 by means of the screws 35, which may be placed in position before the base member 20 is fitted over the upstanding vertical flange 19 of the base unit C. Therefore, it 45 will be understood that when one or more cabinets are set up side by side, and it is not necessary to provide a complete separating wall therebetween, the fastenings which 50 are utilized for anchoring the adjacent cabinets together by passing through the openings 34, also serve to hold the panels 29 in place, but on the other hand when it is desired 55 to provide a finished side wall for the cabinet, the said side wall S is secured in position by the screws 35 which are concealed by the base panel or apron 20.

In assembling the several units to form a 60 complete cabinet, the back section A is first held in a vertical position and the holding flange portions 13 of the rear uprights of the side ladder sections B—B are placed into the keeper channels of the side flanges 2 of the back section. After the side and back

sections are thus connected the spacer rods 16 are sprung into position, thus holding the stiffening angles 14 and the back and side sections in assembled relation. The bottom unit C is then preferably next placed in position by placing its down-turned flange portions into interlocking engagement with the holding flange 8 of the back section and clips 8^a of the side sections B—B. 70

The top section D is then placed in position by holding the front end slightly elevated and sliding the keeper flange 22 between the angle plate 5 and the inturned wall 3 of the back section A. When the rear edge of the top section and the back unit A are thus connected and the front of the top is still held elevated, the upper transverse member 28 of the front ladder section E is placed behind the inturned flange 25 at the front of the top, as shown in Fig. 6, the entire front section E is then swung inwardly into position between the flanges 9^b of the opposite side sections B—B, and the top and front sections thus connected are lowered together. The top D and front E 90 are hingedly interlocked, so that when the lower part of the front unit, acting as a lever, is swung into place the top is placed under tension to make a stable structure. When the front unit is in position the panels 95 29 may be fitted over the mating parts of the front and sides to lock the said front section securely in position in the manner already referred to. In event that the solid side walls S are utilized these will of course take 100 the place of the panels 29, the same being secured in place by the screws 35 as already referred to, and also by suitable fastenings inserted in the openings 36 of the rear vertical uprights 10 of the side sections. 105

With the foregoing arrangement it will be apparent that the joint between the side sections B—B and the back unit is located at the side of the cabinet. However, in case it is desired to locate the joint at the back of the cabinet, instead of at the side the modified construction shown in Fig. 9 of the drawings may be utilized. In this form of embodiment the opposite side edges of the body 1^x of the back section A are provided with the flanged angle portions 2^a whose inner angles face outwardly instead of inwardly as in the form of construction shown in the other figures of the drawings. These flanges 2^a are in this case preferably provided with a slot 37 for registering with a similar slot in the interior reinforcing angle strip 14^a and the inturned flange 38 of the side panel section S', whereby a suitable key 39 having a forked slot 40 may be inserted in the inside of the cabinet the narrowest part of the form engages and clamps together the stiffening angle 14^a, flange 2^a and flange 38 of the side section. For the purpose of retaining the lower corner of the 110 115 120 125 130

joint an ear 41 may be formed on the bottom flange 1^b of the back plate, the same being bent upwardly to engage the return flange 38 of the side plate or section.

5 Without further description it is thought that it will be clearly apparent that the present invention proposes to provide a cabinet construction consisting of a plurality of interfitting units or sections which may be 10 readily knocked-down for shipment in a compact form and on the other hand readily and quickly assembled to provide a single cabinet or a row of cabinets as desired, while at the same time providing for the effective 15 exclusion of dust or other foreign matter from the interior of the cabinets through the utilization of novel joints where the several parts connect or meet. Further these novel joints contribute materially to 20 the strength and rigidity of the entire cabinet structure.

We claim:

1. A knock-down metal furniture construction including a back section, side sections detachably interlocked at the rear to the side edge portions of the back sections, a front ladder section, and connectors detachably holding the front ladder section interlocked with the front portions of the side 30 sections.

2. A knock-down metal furniture construction including a back section, side sections detachably interlocked at the rear with the side edge portions of the back section, a front ladder section interfitting with the front portions of the side sections, and panel members adapted to detachably lock the front and side ladder sections together.

3. A knock-down metal furniture construction including a back section, side sections detachably interlocked at the rear with the side edge portions of the back section, a front ladder section, and panel members arranged at the sides of the side sections 45 and having an engagement with the front ladder section to hold it detachably interlocked with the side sections.

4. A knock-down metal furniture construction including a back section, side sections detachably interlocked at the rear with the side edge portion of the back section, a front ladder section, and panel members of substantially U-shaped cross section for embracing the meeting edges of the front 55 and side sections and holding the same in interlocked engagement.

5. A knock-down metal furniture construction including a back section, side sections detachably interlocked at the rear with the side edge portions of the back section, a front ladder section, and panel members consisting of spaced parallel walls connected by a transverse web, one of said walls being notched to fit over the transverse members 65 of the front ladder section when the panel

member is fitted to the meeting edges of the front and side sections to hold the same in their locked relation.

6. In a metal furniture construction, a back wall member provided at its opposite vertical edges with an inturned flange, side wall members each provided at one edge with an outturned flange interfitting within one of the inturned flanges of the back wall, and means disposed between the flanges of the side walls to hold the same interlocked with the flanges of the back wall.

7. A knock-down metal furniture construction including a back section having marginal keeper grooves opening inwardly, side sections having outturned portions adapted to fit in said keeper grooves, and spacing rods adapted to be interposed between the inside faces of the side sections to maintain the same in locked engagement with the back section.

8. A knock-down metal furniture construction including a back section having its opposite side edges provided with flanges forming keeper grooves, side sections including vertical front and rear members and horizontal drawer guides connecting said members, and the rear vertical members of the said side sections having an interlocking engagement with the keeper grooves of the back section, vertically disposed angle members adapted to be fitted in the interior angle formed between the rear vertical members of the side sections and the back section and provided with perforations for registering with similar perforations in said vertical members, and spacing rods having locking end portions adapted to fit in said openings and hold the rear vertical members of the side sections in locked engagement with the back section.

9. A knock-down metal furniture construction including a back section having marginal inwardly facing keeper grooves, side ladder sections consisting of front and rear vertical members and transverse drawer guides, the said rear vertical members being provided with outturned flanges for engaging with the inwardly facing keeper grooves of the back section, and the front vertical members of said side sections being formed with flanges providing interior angles which constitute a front section receiving seat, and a front ladder section adapted to be detachably fitted into the seat formed by the included angles of the flanges of the front members of the side ladder sections.

10. A sectional cabinet construction including a back section, side sections having an interlocking engagement with the side edges of the back section, means for rigidly spacing and holding the side sections in place with reference to the back section, a front section adapted to have an interlocking fit with the forward edges of the side

sections, a flanged bottom section interlocking with the back and side sections, means for locking the front section to the side sections, and a cap section having a slidable 5 interlocking engagement with the back section and a telescoping relation with the front and side ladder sections.

11. A sectional cabinet construction including a back section consisting of a closed 10 wall, skeleton side sections including front and rear upright members and horizontally disposed drawer guide members rigidly connected with said front and rear uprights, means for locking the rear uprights with 15 the back section, a skeleton front section adapted to be secured to the front edges of the side sections, and cap and base sections having an interlocking fit with the back, side, and front sections.

20 12. A sectional metal cabinet construction including interlocking back and side sections, means for holding the same in interlocked relation, a base section having an interlocking engagement with the back and 25 side sections, and said side sections being provided with seats, a front ladder section adapted to be held in said seats and consisting of vertical upright members and transverse drawer dividing members, and a cap 30 section having an interlocking engagement with the back and front sections and a relatively telescoping engagement with the side sections.

13. A knock-down metal furniture construction including a back section, a front 35 ladder section, side ladder sections consisting of front and rear vertical members of channel formation and a plurality of transverse drawer guides connecting said members, the rear vertical members of said side 40 sections being provided with flanges for interlocking with the back section and relatively wide abutment flange facing outwardly from the cabinet, and said front 45 vertical members also having outwardly facing abutment flanges lying in substantially the same plane as the abutment flanges of the rear vertical members, and the forward flanges of said front vertical flanges providing inwardly facing seats for said front 50 section.

14. A knock-down metal furniture construction including a back section provided with keeper means at its top edge and keeper 55 grooves at its side edges, side sections adapted to interlock with the keeper grooves at the sides of the back section, a front section adapted to fit between the front edges of the side sections, means for holding the 60 side sections interlocked with the back section, and a cap section provided with a keeper flange at its rear edge for engaging

with the keeper means at the top edge of the back section, and also provided with keeper means at its front edge for engaging 65 with the upper portion of the front section.

15. A knock-down metal furniture construction including a back section having keeper means at its top, side and bottom edges, side ladder sections having means at 70 their rear edges for interlocking with the side edges of the back section and also provided with keeper means, means for holding the side sections interlocked with the back section, a bottom section having a flanged 75 skirt portion adapted to interlock with the keeper means at the bottom of the back section and also with the keeper means of the side sections, a front ladder section adapted to fit between the front edges of the side sections, and a cap section having a slidable interlocking engagement with the keeper 80 grooves at the top of the back section, and having a flange at its front edge for embracing the uppermost transverse member of 85 the front ladder section, and panel members adapted to embrace the meeting edges of the front and side sections to hold the assembled structure in position.

16. A metal furniture construction including back and side sections separably interlocked, a top section interfiting with the back and side sections, and a front section having an interlocking engagement at the 90 top with the top section and also having a 95 fulcruming engagement with the side sections to place the same under tension.

17. A metal furniture construction including back and side sections separably interlocked, a top section interfiting with the 100 back and side sections, and a front section having a hinged interlocking engagement at the inner edge portion of the top with the top section whereby when the front section is swung into place against the side sections, the interfiting parts are held under 105 tension.

18. A metal furniture construction including back and side sections separably interlocked, a top section slidably interfiting with the top of the back section, and a side section engaging the top and side sections and arranged to fulcrum against the side sections to operate as a tensioning lever to 110 place the top and interfiting parts under 115 tension.

In testimony whereof we hereunto affix our signatures in the presence of two witnesses.
